UNITED STATES PATENT OFFICE

156,447

VEHICLE SERVICE TRAY HOLDER

Ethel L. Maddox, Macon, Ga., assignor of one-half to Dulane S. Maddox, Macon, Ga.

Application June 11, 1948, Serial No. 146,907

Term of patent 7 years

(Cl. D14—6)

To all whom it may concern:

Be it known that I, Ethel L. Maddox, a citizen of the United States, residing at Macon, in the county of Bibb and State of Georgia, have invented a new, original, and ornamental Design for a Vehicle Service Tray Holder, of which the following is a specification, reference being had to the accompanying drawing, forming part thereof.

Figure 1 is an outside perspective view of a vehicle service tray holder, showing my new design, and

I claim:

The ornamental design for a vehicle service tray holder, as shown.

ETHEL L. MADDOX.
